Henry Hornbostel,

By Attorneys,

John T. Fraser T.C.

UNITED STATES PATENT OFFICE.

HENRY HORNBOSTEL, OF NEW YORK, N. Y., ASSIGNOR TO THE HENRY HUBER COMPANY, OF SAME PLACE.

DESIGN FOR A LAVATORY-SLAB.

SPECIFICATION forming part of Design No. 33,308, dated October 2, 1900.

Application filed July 5, 1900. Serial No. 22,637. Term of patent 14 years.

To all whom it may concern:

Be it known that I, HENRY HORNBOSTEL, a citizen of the United States, residing in New York, in the county of New York and State 5 of New York, have invented and produced a new and original Design for a Lavatory-Slab, of which the following is a specification.

This design relates to a lavatory-slab.

The new design relates to the shape or configuration and also to the surface ornamentation of a lavatory-slab.

My present design is shown in the accompanying drawing, which is a perspective view of the top or obverse side of a lavatory-slab 15 embodying the new design.

Referring to the drawing, A represents a lavatory-slab; B, the front part thereof; C, the rear part thereof; D, the sides; E, the aperture, and F the top surface.

20 A distinctive feature of the new design exists in the shape of the aperture E, which in its general extent is a distorted ellipse in outline, the portion *a* at the front side of its longer axis *b* being substantially semi-elliptical, and the portions *e* at the rear side of its longer axis being distorted rearwardly in the form of two distinct arcs which meet in an obtuse angle on the line of the shorter axis *f*, so that the rear side has the appearance 25 of a flat Corinthian arch, while the front side and the ends of the aperture appear elliptical.

Another distinguishing feature of my design is that the front B and the ends D of the 30 slab are in general of elliptical outline, while the rear C thereof is a projection in the direction of the shorter axis of the ellipse and has a rectilinear rear wall *g*, angular side walls *h*, and curves *i* uniting its side walls 35 with the elliptical walls of the slab.

Another distinguishing feature in the shape of the slab is the disposition of the approximately-elliptical aperture E, eccentrically in the approximately-elliptical slab A. The recess is disposed with its longer axis considerably in front of the longer axis *j* of the slab. The result of this eccentricity is that the top of the slab consists of a narrow band *k* of less width at the front of the slab and of gradually-increasing width as it extends from that point to the rear, where it has wide portions *l*.

A feature distinctive of my design is that the outer surface of the slab has an elevated bead-like portion *m* surrounding it of less width at the front and of increasing width as it approaches the rear, that the inner side of the band *k* has a narrow bead-like elevation *n* surrounding it, and that the intermediate portion of the band *k* between the beads is depressed there, as well as at the points *o* between the different portions of the beads. At rear the slab has a smooth top *p*, across which the elevation *m* is perceptible, and the sides of which at *q* the outer and inner beads are connected by reverse curves.

The new design is distinctive and pleasing in appearance.

What I claim is—

The design for a lavatory-slab, substantially as herein shown and described.

In witness whereof I have hereunto signed my name in the presence of two subscribers.

HENRY HORNBOSTEL
